UNITED STATES PATENT OFFICE.

JAMES C. REID, OF CLEVELAND, AND WILLIAM C. TAYLOR, OF EAST CLEVELAND, OHIO.

TOE-PLATE FASTENER.

Application filed June 2, 1922. Serial No. 565,356.

To all whom it may concern:

Be it known that we, JAMES C. REID, of Cleveland, and WILLIAM C. TAYLOR, of East Cleveland, in the county of Cuyahoga and State of Ohio, have invented new and useful Improvements in Toe-Plate Fasteners, of which the following is a specification.

This invention relates to implements employed mostly in shoe stores and repair shops for affixing metallic wearing plates to the toe sections of the soles of shoes.

Metallic toe-plates furnished to shoe dealers and repairmen are usually applied to shoes in a crude manner by slipping the shoe over an iron last and pounding the plate into the sole with a hand hammer. This operation flattens the crown of the plate and otherwise distorts it, and seldom sets it flush with the sole. Moreover, the hammer or the last may be mislaid, resulting in confusion and delay while customers are kept waiting.

The prime objects, therefore, of our present invention are to provide simple, efficient and convenient means for fastening toe-plates to shoes quickly, firmly, and in a workmanlike manner, without distortion or undesirable upsetting or tilting of the plates; and to produce a self-contained device of this character always ready to perform its functions, and which may be fixedly secured upon a counter or other convenient support. Another important object is to provide plate pressing means readily movable toward and from the last or anvil to facilitate the placing of the shoe upon and its removal from said last. Further objects are to provide for setting different forms of toe-plates; and to produce an arrangement of parts readily assembled or taken apart for packing in a small parcel.

Minor objects will become apparent from the following description of a preferred embodiment of our invention, reference being had to the accompanying drawing, in which—

Fig. 1 is a side elevation of an assembled machine, the dotted lines indicating the slideable press in its rearward position, and the toe part of a shoe upon the last.

Fig. 2 is a rear end view of the device with the hand lever in its upright position.

Fig. 3 is a plan view of Fig. 1.

Fig. 4 is a fragmentary side view, partly in section, of the press-ram and its housing.

Fig. 5 is a bottom view of a popular type of metallic toe-plate, the dotted outline in-

dicating the toe of a shoe on which the plate is set.

Fig. 6 is a side view, and

Fig. 7 is a front view of the toe-plate shown in Fig. 5.

The reference numeral 1 indicates a narrow, blunt-pointed and flat-topped metallic toe-last, or anvil member, resembling in plan view a broad spearhead; being integral with 65 and supported upon a flat-sided gooseneck 2 extended forward and downward in a semicircle, and having beneath it a laterally projecting base-plate 3. Holes are made in the base-plate 3 for screws 4, by which the 70 device may be secured upon a counter, or other supporting structure 5. The gooseneck support 2 merges at its lower end in a guidebar 6 of rectangular or I-shaped section extended horizontally some distance to 75 the rear of the base-plate, and adapted to carry the slideable standard of the pressing device 7; the bottom of said standard being looped about one or more rectangular apertures 8, Fig. 2, fitted to slide loosely upon the 80 bar 6; and a spaced apart pair of said loops 9, 9, Figs. 1 and 3, is preferred to a continuous loop.

The front face of the standard 7 is vertical to a point higher than the last 1, where 85 an overhanging bracket is formed, which bracket supports an upright housing and guideway 10 for a ram 11 of rectangular cross-section adapted to reciprocate vertically in said guideway. The lower end of 90 the ram 11 is hollowed out forming a concavity 12 approximately fitting the convex crown of a toe-plate, such, for example, as the common type 13 shown in Figs. 1, 5, 6 and 7, which has a dished body with three 95 prong-like claws 14 thereon bent over at right angles to the plane of its edges. For operating the ram 11 various known machine elements for effecting leverage and retrieving are suitable, but we have shown and 100 will now describe a preferred form.

The upper part of the guideway 10 is bifurcated, and its lateral branches terminate above in rounded oppositely disposed ears 15, 15 drilled to receive a closely fitted bolt 105 or bearing pin 16 preferably, though not necessarily, set slightly forward of the vertical axis of the ram. A hand lever 17 has its front end portion flattened vertically to fit loosely between the branches of the guideway 10, and drilled to form a fulcrum bearing on the pin 16. The front and lower

faces of the flat part of the lever 17 are curved to form a cam, as at 18, eccentric or involute to the pin 16, the curve receding from the pin toward the lower face of the lever; and said cam face 18 bears upon the top of the ram 11. A projecting stop 19 is adapted to abut against the front face of the ram 11 and retain the lever 17 in an upright position, as shown in Fig. 2, and in 10 dotted lines in Fig. 1.

A transverse groove or notch 20 is formed in the rear side of the ram 11 to receive the free end of a retrieving spring 21, which is a leaf spring fitted to oscillate vertically between the upright branches of the guideway 10, and formed with any suitable bends adapting it to press the ram upward against the cam face 18 of the hand lever. A bracket 22 projects rearwardly from the top of the standard 7, to which the fixed end of the spring 21 is secured by a screw 23, or other suitable means. The screw-hole in the spring 21 may be slotted lengthwise of the spring, so that merely loosening the screw 23 will permit the spring to be slipped out of the notch 20, whereupon the ram 11 will drop out of its guideway 10, and another ram having a different stamp formation 12 may be inserted in the guideway. The ram 11 may also be 30 removed through the top of its guideway without loosening the spring screw 23, by withdrawing the fulcrum pin or bolt 16.

When the machine is assembled a stop pin or screw 24 is secured in the rear end of the 35 guidabar 6 to limit the backward movement of the pressing device 7 at the position shown in dotted lines in Fig. 1. In this position ample room is provided for slipping a shoe over the last 1, as indicated by dotted lines 25, Fig. 1. The sharp claws of a toe-plate 13 being lightly pressed by hand to locate it in the sole of a shoe on the last, the press 7 is slid forward and manipulated to bring the ram 11 over the toe-plate, whereupon a downward thrust of the hand lever 17 drives the ram hard against the toe-plate and sinks the latter firmly in the sole. If desired the lower end of the ram 11 may be magnetized so that it will hold a steel or 50 iron toe-plate in the concavity 12, thus avoiding the preliminary setting of the plate on the sole of the shoe.

We further point out and distinctly claim as our invention—

55 1. A toe-plate fastener for shoes comprising a fixed guidebar merged at one end in a semicircular stanchion supporting a last, and a pressing device slidably embracing said guidebar and having a lever-operated ram adapted to be manipulated to overhang and oppose said last.

60 2. In a toe-plate fastener for shoes, a last member comprising a horizontal guidebar having a base-plate at one end and merged 65 above the base-plate in a stanchion support-

ing a flat-topped last, said stanchion being curved so that the last top parallels and overhangs the guidebar; and a pressing device slidably embracing said guidebar and having a lever-operated ram adapted to be positioned to overhang and oppose said last. 70

3. A toe-plate fastener for shoes comprising a fixed guidebar merged at one end in a semicircularly bent stanchion supporting a last, said last having its upper surface parallel with and overhanging said guidebar; and a pressing mechanism slidably embracing said guidebar and having a lever-operated ram provided with a terminal concavity adapted to be positioned by hand to overhang and oppose said last. 75

4. In a toe-plate fastener for shoes, a last imposed upon a semicircularly bent stanchion merged at its lower end in a guidebar, a standard slibably embracing said guidebar 80 and movable in the plane of said stanchion, and pressing mechanism on said standard having a lever-operated ram adapted to be positioned to overhang and oppose said last.

5. In a toe-plate fastener for shoes, a last imposed upon a semicircularly bent stanchion merged at its lower end in a guidebar, a standard looped about said guidebar at its foot and slidale thereon in the plane of said stanchion, a guideway bracketed out from 90 the front of said standard, a spring-retrieved ram fitted to reciprocate vertically in said guideway and oppose said last, and means for applying leverage to depress said ram. 95

6. In a toe-plate fastener for shoes, a last imposed upon a return-bent stanchion merged at its lower end in a guidebar, a standard looped about said guidebar at its foot and slidale thereon in the plane of said stanchion, a guideway bracketed out from 100 the front of said standard having its upper part bifurcated, a ram fitted to reciprocate vertically in said guideway and oppose said last, a spring member adapted to lift said ram, and a lever fulcrumed in the bifurcation of said guideway and provided with 105 means for depressing said ram. 110

7. In a toe-plate fastener for shoes, a last imposed upon a return-bent stanchion merged at its lower end in a guidebar, a standard embracing said guidebar at its foot and slidale thereon in the plane of said stanchion, a guideway bracketed out from 115 the front of said standard having its upper part bifurcated, a ram fitted to reciprocate vertically in said guideway in opposition to said last and having a transverse groove in its rear side, a spring member removably secured to said standard and engageable in said groove to lift the ram, and a lever fulcrumed in the bifurcation of said guideway 120 provided with a cam for depressing said ram. 125
